DESIGN FOR A SIGN BOARD

**Morris L. Rosenbush, Kokomo, Ind., assignor to
National Sign Corporation, Kokomo, Ind., a
corporation of Indiana**

Application November 15, 1934, Serial No. 54,027

Term of patent 3½ years

To all whom it may concern:

Be it known that I, Morris L. Rosenbush, a citizen of the United States, residing at Kokomo, in the county of Howard and State of Indiana, have invented a new, original, and ornamental Design for a Sign Board, of which the following is a specification, reference being had to the accompanying drawing in which,

Fig. 1 is a front elevation of a sign board showing my new design; and

Fig. 2 is a rear elevation thereof.

The primary feature of the design comprises

an arrow-shaped figure so delineated relative to that area of the sign which flanks the head end of the arrow-shaped portion that, when the sign as a whole is viewed by an observer, the arrow-shaped figure appears to be lying in a plane intersecting the plane of the aforesaid flanking area at a substantial angle, substantially normal to the aforesaid flanking area.

I claim:

The ornamental design for a sign board as shown and described.

MORRIS L. ROSENBUSH.
